US00D879234S

(12) **United States Design Patent** (10) Patent No.: **US D879,234 S**
Barfoot et al. (45) Date of Patent: **** Mar. 24, 2020**

(54) **FIREARM STOCK**

F41C 7/06; F41C 7/11; F41C 7/12; F41C 27/00; F41C 27/06

See application file for complete search history.

(71) Applicant: **Magpul Industries Corp.**, Austin, TX
